ART OF CASTING FIBER ARTICLES

Application filed June 19, 1930. Serial No. 462,216.

This invention relates to improvements in the art of casting fiber articles. It is the object of the present invention to provide a novel and improved casting apparatus and method for the manufacture of fiber articles of a form which may be characterized as bulbous in that there is an interior cavity of larger size than the neck of the mold upon which the article is cast.

10 More particularly stated, it is our purpose to provide means for the use upon a standard foraminous mold, or otherwise, of a porous body which may comprise a mold extension, and which is preferably in the form of a split 55 ring of felt or the like having sufficiently flexible characteristics so that upon completion of the casting operation the felt-like body may be drawn from the cast article (following the withdrawal of the metallic 60 portion of the mold, if such a mold portion is used). The advantages and details of the construction referred to will be more apparent in the light of the following disclosure.

In the drawing:

25 Figure 1 is a fragmentary detail in section, of a vat, and a diagrammatic illustration of the immersion therein of a mold fabricated in accordance with this invention and adapted for the casting of a bulbous article.

30 Figure 2 is a view similar to Fig. 1 but showing the deposit, on the surface of the composite mold, of the fiber particles suspended in the fluid of the vat.

Figure 3 is a diagrammatic illustration of 35 the cast article and fibrous portion of the mold in section as they appear upon withdrawal of the core of the mold.

Figure 4 is a view in a section similar to that of Fig. 3, showing the withdrawal of 40 the fibrous portion of the mold from the cast article.

Figure 5 is a detail view in section taken in the horizontal plane indicated at 5-5 in Fig. 2.

45 Like parts are identified by the same reference characters throughout the several views.

It has for a great many years been standard commercial practice to mold or cast papier-mâché articles by immersing a foraminous mold in a vat containing a suitable

liquid such as water, in which particles of macerated paper are suspended, and by exhausting the contents of the foraminous mold by suction to cause the water of the vat to pass through the mold and deposit the paper particles upon its surface to any desired depth. In practice, however, this process has been definitely limited in its operation due to the difficulty and expense of providing and manipulating any suitable form of collapsible mold enlargement which would permit of the production of bulbous vases or other utensils, the term "bulbous" being used to define any article having an interior cavity larger than the neck portion through which the mold must be withdrawn.

In the practice of the present invention we employ a foraminous mold 10 which may conveniently be made of screening or sheet metal punched with holes. The interior of this mold is connected by a pipe 11 and hose 12 with a suitable pump for exhausting the air and water from the device. We contemplate the use within the mold, of a displacement body 13 which will minimize the amount of air and water which must be withdrawn prior to the deposit of papier-mâché on the surface of the mold.

It will be noted that the foraminous mold 10 flares at its upper end, whereas its lower end portion 14 tapers more gradually and is preferably approximately cylindrical. In order to create the desired bulbous form of the completed article we prefer to employ upon the mold 10 a mold extension 15 which may conveniently be made of skived felt or any other suitable porous body, including sponge rubber, cork, asbestos, and textiles. The object is merely to provide a porous mold extension which may be cut or wound to the desired external contour and is sufficiently flexible to permit of its withdrawal through the neck of the proposed cast article. Felt has been found to be particularly suitable and may readily be carved or skived to the desired contour and made up in the form of a split ring having tapering overlapping ends, as shown in Fig. 5.

The form of a body of felt is less subject to distortion and is more easily attained than

the form of an ordinary foraminous metal mold. It is also very cheap, and while it may be used repeatedly it may also, in special cases, be allowed to remain in the casting 5 where desired, and for this purpose a very cheap form of rough felt may be used. As an illustration we have shown a pad 16 of rough felt applied to the lower end of the foraminous metal mold member 10 to provide 10 a hollow base for the completed cast article in which this pad 16 may be left for convenience. Obviously, it might also be withdrawn if desired, and it will be understood that the disclosure in this respect is merely illustrative.

The portions of the foraminous member or mold 10 which are covered by the felt or the like need not have the small openings which are characteristically found in the remaining 20 wall of the mold member 10. Any size of opening is sufficient which provides adequate support for the felt and a sufficient communication between the interior of the felt mat and the interior of the foraminous support. 25 In fact, in special instances the mold, as shown in Figs. 1, 2 and 3, may be eliminated and a properly formed mass of felt placed directly in communication with the discharge pipe 11. In effect, the felt mass 16 functions 30 exactly as if the intervening mold member 10 were eliminated.

It will also be obvious that where desired the felt or similar body used in the device, or a series of such bodies, may be used to cover 35 the entire exposed surface of the foraminous member 10. For illustration, however, we have chosen to show a mold which comprises in part the foraminous member 10, and in part the felt body 15 within which the lower 40 end portion 14 of the foraminous member 10 is merely a core. It is because of the actual use in part, of the foraminous member 10 to define the form of the cast article, that the foraminous member flares so widely at its upper end portion.

The foraminous member 10, assembled as above described upon the suction pipe 11 and bearing the porous mold extensions 15 and 16, is lowered into the vat 17 which is filled with 50 water or other suitable liquid at 18, in which the particles 19 of macerated paper are suspended. The vacuum applied through pipe 11 and hose 12 quickly sucks all the air from the mold apparatus, and water immediately 55 commences to flow into the mold through the openings of the foraminous member 10 and the pores or interstices of the felt or like fibrous bodies 15 and 16.

While the holes in the foraminous mold are 60 shown comparatively large for convenience of illustration, it will be understood that they are in practice very small. In fact it is usual in the art to use a fine screen or gauze for the mold member, or as a cover therefor, so that 65 as the water flows through the mold its con-

tent of paper, wood, leather or asbestos fiber, or other fibrous material will be deposited on the surface of the mold and mold extension.

When a deposit of paper or the like (other macerated materials than paper may be used) 70 has reached a required depth upon the composite mold, as shown in Fig. 2, the mold and the article cast thereon are removed unitarily from the vat and, if the vat contains water or other liquid, a drying operation is 75 desirable. The drying operation is mentioned conditionally for the reason that the process may be practiced even in a body of gas instead of water, where the material to be deposited on the mold is sufficiently light 80 with reference to the fluid supporting it, so that the fluid used may comprise a gas.

The core portion of the mold is now freed from the mold extension and from the cast article by connecting pipe 11 with a source of air under pressure instead of a source of partial vacuum. The compressed air blows the completed article from the mold, and this method of freeing the foraminous portion of the mold from the article is preferred even 90 where the shape of the core is such that the mold could be pulled therefrom. The air under pressure tends to force out of the small openings in the mold any fibrous or paper particles which are partially intruding therein, and thus leaves the foraminous member 95 clean for a succeeding mold operation.

The next step in the completion of the cast article consists in withdrawing therefrom the mold extension upon which has been 100 deposited the bulbous body of the article. This is done, as illustrated in Fig. 4, by simply inserting a hook through the mouth of the cast article and pulling upon one of the overlapping free ends of the felt ring 15. The felt ring readily opens up helically and is 105 sufficiently flexible to pass readily through the mouth of the article. If the article is of such a shape that one ring will not pass readily through its mouth it will be obvious that a number of rings of short axial extent may be superimposed to build up the desired contour.

It is to be understood that although we have referred in this application to the use of suction as a means for producing fluid flow through the wall of the mold to deposit the suspended particles thereon, we are mindful of the fact that any means of establishing the necessary pressure differential may be used for the purposes of the present invention. We contemplate the use of a sealed vat 17 and a ram for placing high pressures on the surface of the fluid therein sufficient to force the fluid from the vat through the wall of the mold, and to an overflow point in pipe 11. In so doing, the back pressure of the fluid in pipe 11, if that fluid be relatively heavy, as in the case of a liquid, will tend to create a very dense deposit of sus- 115 120 125 130

pended matter on the wall of the mold. This slightly modified process therefore may be used where articles of high density and low porosity are required. It offers a way of preserving the naturally rough texture of the pulp deposits which would be destroyed by the pressure of a female die member instead of the fluid pressure as suggested.

We claim:

- 10 1. Casting apparatus of the class described, comprising the combination with a discharge pipe, of a porous body with the pores of which said pipe communicates, said body having exposed surfaces of the desired contour of the article to be cast, characterized by a dimension greater than an opening in said article, a pulp container and means for establishing a pressure differential between said container and pipe whereby to 20 deposit pulp on said porous body, said porous body being deformable sufficiently to permit its removal through said opening.
- 25 2. Casting apparatus of the class described, comprising the combination with a discharge pipe and a hollow foraminous member communicating therewith, of a porous body of desired contour characterized by a dimension in excess of an opening in an article to be cast thereon and applied to a portion of said foraminous member and constituting an extension of the surface thereof, said body being deformable sufficiently to permit withdrawal thereof through said opening.
- 35 3. Casting apparatus of the class described, comprising the combination with a hollow foraminous member having a discharge opening and of such form as to be withdrawable from a casting, of a highly porous 40 mold extension of a form characterized by a dimension when applied to a portion of said member in excess of the capacity of an opening in said casting and having its pores communicating through a foraminous wall of 45 said member with the interior thereof, said extension being sufficiently deformable for removal from said casting through said opening.
- 50 4. Casting apparatus of the class described, comprising the combination with a hollow foraminous member having a discharge opening and of such form as to be withdrawable from a casting, of a highly porous mold extension applied to a portion of said member 55 and having its pores communicating through a foraminous wall of said member with the interior thereof, said mold extension comprising a body of felted fiber, larger, when applied to said member, than an opening in 60 said casting, and sufficiently deformable, when said member is withdrawn, to be removed from said casting through said opening.
- 65 5. Casting apparatus of the class described, comprising the combination with a hollow

foraminous member having a discharge opening and of such form as to be withdrawable from a casting, of a highly porous mold extension applied to a portion of said member and having its pores communicating through a foraminous wall of said member with the interior thereof, said mold extension comprising a ring-like body of felt of an external contour corresponding to the desired shape of the article cast thereon, of an effective size larger than an opening in said casting and from which said foraminous member is retractile, said extension being sufficiently deformable to be withdrawn from said casting through said opening.

6. Casting apparatus of the class described, comprising the combination with a hollow foraminous member provided with an exhaust passage and of which a portion constitutes a mold and another portion constitutes a core, of a highly porous body detachably applied to the core portion of said foraminous member with its pores in communication through said member with the interior thereof and the exhaust passage, whereby said member and body together constitute a mold.

7. Casting apparatus of the class described, comprising a tapered core member having an apertured wall and an exhaust port, of a felt body surrounding an apertured portion of said member and freely removable from the tapered end thereof, said body having an external contour corresponding to that of the article to be cast and communicating through its pores with the interior of said member.

8. Casting apparatus of the class described, comprising a hollow foraminous member provided with a discharge port, and a felt-like body in the form of a split ring detachably applied to a portion of said member having openings through which said felt communicates with the interior of said member.

9. Casting apparatus of the class described, comprising the combination with a hollow mold member provided with a wall having openings, of a plurality of preformed felt bodies applied to the openings in said wall and adapted to constitute mold extensions of said member.

10. A casting process of the class described, comprising building up a mold with a removable porous body comprising an extension of the mold and of a size larger than an opening in an article cast thereon, depositing material on the surface of the mold and mold extension, and withdrawing the mold from said body and the article cast thereon.

11. A casting process of the class described, comprising building up a mold with a removable porous body comprising an extension of the mold of an effective size larger than an opening in an article cast thereon, depositing material on the surface of the mold and mold extension, withdrawing the

mold from said body and the article cast thereon, and subsequently deforming and withdrawing the body from the article through said opening.

5 12. A casting process of the class described, comprising the immersion of a fibrous mass of predetermined contour in a fluid in which particles are suspended, creating a pressure differential between said fluid and an interior portion of said mass, whereby to circulate fluid through said mass and deposit said suspended material on the surface thereof.

15 13. A casting process of the class described, comprising the shaping of a felt-like mass to desired contours and connecting a portion thereof to a discharge port while exposing other portions thereof to a fluid in which particles are suspended under pressures exceeding those in the port.

20 14. As a new article of manufacture, a mold member comprising a porous flexible body of substantial thickness having a normal annular form with free ends in substantial abutment.

25 15. As a new article of manufacture, a mold member comprising a flexible porous body of annular form and substantially uniform thickness throughout its circumferential extent in any given plane normal to its axis, the ends of said body being free and contiguous.

30 16. As a new article of manufacture, a mold member comprising a flexible porous body of annular form and substantially uniform thickness throughout its circumferential extent in any given plane normal to its axis, the ends of said body being free and contiguous in overlapping relation, said ends being of complementary form and tapering thickness whereby to overlap without varying the aforesaid uniformity of thickness of said body.

35 17. Casting apparatus comprising the combination with an apertured support, of a highly porous flexible body removably wound on the support.

40 18. Casting apparatus comprising the combination with an apertured support, of a highly porous flexible body removably wound on the support, said body having substantially uniform thickness in a given plane normal to the axis of the support and having an overlapping end engageable for the purpose of unwinding said body.
